WINDING MACHINE

Thomas N. Carter, Bayside, and Alexander D. Frascella, Brooklyn, N. Y., assignors to Cameron Machine Company, Brooklyn, N. Y., a corporation of New York

Application December 23, 1949, Serial No. 134,751

6 Claims. (Cl. 242—66)

1

This invention relates to machines for winding webs of flexible material into rolls.

Web-winding machines commonly employed have two surface winding rollers rotatable in the same direction and spaced apart for supporting a core or a winding shaft in the valley between the rollers. As the winding rollers rotate they frictionally engage the surface of flexible material on the winding shaft and cause the shaft to rotate and a roll of material to form. A riding roller rests upon the roll of material and rises as the diameter of the roll increases during a winding operation. The path of movement of the riding roller is determined by a pair of arms which extend from a pivot shaft and carry the bearings for the roller. The riding roller is part of a weighted system which is effective on the pivot shaft and causes the riding roller to exert pressure on the roll of material. Means are provided for lifting the riding roller from a completed roll of material and after the roll has been removed from the machine and a fresh winding shaft has been placed the riding roller is lowered for another winding operation.

These lifting and lowering operations heretofore have been accomplished under manual control by the use of a foot treadle and linkage connecting the treadle with the pivot shaft. The use of a mechanical connection of this kind requires care for assuring that the riding roller system will not inadvertently slip and permit the riding roller to fall and damage itself or the winding shaft, or crush the operator's fingers. The riding roller is relatively heavy and its manipulation by an operator incident to each winding operation tends to tire the operator and decrease his efficiency.

It is among the objects of the invention to conserve the energy of an operator by providing a winding machine which relieves the operator of the necessity of manually elevating the riding roller between winding operations and of responsibility for the careful lowering of the riding roller whereby to eliminate the probability of damage and accidents due to a falling riding roller. The mechanism whereby these and other objectives are attained involves the use of a reversible motor which drives a one-way clutch through speed reducing mechanism and in which the clutch is connected for rotating the pivot shaft to lift or elevate the riding roller when the motor is operated in one direction. With this mechanism the riding roller may be raised to an elevated position which is determined by a switch whereby the operation of the motor is automatic-

ally discontinued. In view of the irreversible driving characteristics of the gearing of the speed reducing mechanism, and the drive connection of the one-way clutch, the riding roller is held in the elevated position without danger of dropping when the operation of the motor is discontinued.

When it is desired to lower the riding roller onto the material on the winding shaft it is necessary only that the operator reverse the operation of the motor and thereby permit the pivot shaft to rotate in the reverse direction as the riding roller descends under the pull of gravity. The descent of the riding roller is accomplished at a sufficiently low velocity to prevent damaging the roll of material, and it is indifferent as to whether the motor continues to operate after the riding roller comes into contact with the roll of material because the clutch permits the driving shaft to over-run the pivot shaft. With this arrangement the riding roller freely rests upon the roll of material under the pull of gravity provided by the riding roller system, and the riding roller may be raised by hand either during a winding operation, or as the roller is being raised under motor power should the desire to do so arise.

In addition to the power control provided, the winding machine is provided with means whereby the resultant moment of the pivot shaft system can be very closely adjusted to enable the selection of a limitless number of different riding roller pressures within a wide range of pressures so as to enable use of the machine for winding webs of material greatly varying in physical characteristics, and to wind such materials into rolls of desired compactness.

The accompanying drawing illustrates the best mode which has been contemplated for applying the principle of the invention.

Fig. 1 is a front elevational view of a portion of a winding machine illustrating the top-pressure surface riding roller in elevated position and the controlling mechanism therefor;

Fig. 2 is an elevational view taken from the right end of Fig. 1, with parts broken away;

Fig. 3 is an elevational view taken from the left end of Fig. 1;

Fig. 4 is a plan of the mechanism illustrated in Fig. 1;

Fig. 5 is a circuit diagram for the motor by which the surface riding roller is controlled;

Fig. 6 is a section on line 6—6 of Fig. 1; and

Fig. 7 is a section on line 7—7 of Fig. 1 showing the clutch connections.

Referring to the drawing, the winding rollers

10 and 11 are rotatably mounted in bearings in the frame side members 12 and 13 in such a manner as to provide therebetween a valley for supporting the winding shaft 14 (Fig. 2) and the roll of flexible material 15 which is wound around the winding shaft. The web of flexible material 16 is drawn from a supply spool (not shown) and travels over the guide roll 17, measuring roll 18, idling roll 19, winding roller 10 and into the roll of material 15. The top-pressure surface riding roller 20 rests on top of the roll of material 15 and cooperates with the winding rollers 10 and 11 during a winding operation. The winding shaft 14 and the riding roller 20 are displaced upwardly as the diameter of the roll of material increases.

The drive for the winding rollers 10 and 11 and for the riding roller 20 is obtained from a motor (not shown) which is engageable through a clutch to drive the shaft 21, Figs. 1 and 2. It is unnecessary for the understanding of the present invention to explain how power is derived for operating the shaft 21, there being available various forms of mechanisms for serving that purpose. A suitable starting and stopping mechanism is disclosed in the copending United States Patent No. 2,579,791 of December 25, 1951.

The shaft 22 of the winding roller 10 is driven through the pair of gears 23 connecting the shafts 21 and 22, and the winding roller 11 is driven from the shaft 22 by gearing located at the other ends of the roller shafts (Fig. 4) and including an idler (not shown) meshing with gears 24 and 25 attached to the ends of the respective roller shafts. The winding rollers 10 and 11 rotate in the same direction and have the same surface velocity. The operation of a machine of this kind is well-known and, whereas both of the winding rollers 10 and 11 are driven in the machine illustrated, sometimes only one or the other of the winding rollers is driven.

The drive for the top-pressure surface riding roller 20 is obtained from the shaft 22 which carries the winding roller 10, Fig. 4. The drive includes a sprocket and chain connection 27 and a sprocket wheel 28 which is keyed to a hub 29. The hub 29 is rotatably mounted on the reduced end 30 of the pivot shaft for the riding roller 20 which will be more fully described hereinafter. The sprocket hub 29 drives a sprocket hub 31 through a friction disk 32. A sprocket wheel 33 is keyed to the sprocket hub 31 and drives the sprocket wheel 34 on the shaft 35 through the sprocket chain 36. The shaft 35 is rotatably mounted on an arm 37 and a housing 38, the latter of which is carried by an arm 39 which also serves to rotatably support one end of the riding roller 20. The other end of the riding roller 20 is mounted in bearings carried by an arm 40. The riding roller 20 is driven from the shaft 35 through gearing 41. The arms 39 and 40 are fastened to the pivot shaft 42, by which they, together with the arm 37, are rotatable about the axis of the pivot shaft. These arms pivot upwardly as the riding roller rises as the diameter of the material being wound increases. The arms 39 and 40 and the riding roller 20, together with the various other means attached to or supported by the pivot shaft 42, constitute the riding roller system which provides a resultant moment about the axis of the shaft 42 which causes the riding roller 20 to exert pressure upon the roll of material during a winding operation.

To raise the riding roller 20 from the roll of material at the conclusion of a winding opera-

tion, a power drive is provided which acts through a one-way clutch 43. The drive consists of a reversible motor 46 and a speed reducer 47 which constitute a unit whose operation is controlled by a reversible switch 48, which is diagrammatically illustrated in Fig. 5. The reversible switch is operated by a conventional foot pedal (not shown) which, when rocked in one direction from normal position, causes the motor to operate in one direction, and when rocked in the opposite direction towards the normal position causes the motor to operate in the reverse direction.

Having reference to Fig. 1, the motor and speed reducer unit is of standard construction and includes gearing comprising a motor-driven worm 49 and a worm wheel 50 carried by a countershaft 51 within the unit. The ratio of the gearing is such as to rotate the shaft at a moderate speed when the motor is running and to prevent reverse movement of the gearing by the application of a torque from the output side of the unit. The output side of the motor and speed reducer unit is connected to a shaft 52 by suitable gearing 53. The shaft 52 can be rotated only by the motor. The one-way clutch 43 is located intermediate the shaft 52 and the pivot shaft 42. While any suitable one-way clutch may be employed, a clutch which has been found to be satisfactory will be briefly described.

The clutch illustrated in the drawing (Fig. 7) includes an inner race 55, which is keyed to the shaft 52, and an outer race 56 which is keyed to a collar 57. The collar 57 is fastened to the pivot shaft 42 by a pin 58. A plurality of ovate sprags 59, which constitute engageable locking elements, are circumferentially spaced around the inner race 55 of the clutch and are biased to engage the outer and inner races 55 and 56 by a pair of coiled springs 60 and 61 to provide a positive driving connection in one direction between the two races. In the opposite direction of rotation of the inner race the sprags support the outer race. For elevating the riding roller 20 the motor is driven to rotate the shaft 52 counter-clockwise, Fig. 3, and the sprags 59 act to transmit the rotation of the inner race to the outer race and cause the pivot shaft 42 to be rotated. The riding roller 20 may be raised by hand, in which event the sprags 59 automatically become ineffective for transmitting rotation through the clutch and permit slippage between the two races with the outer race over-riding the inner race.

After the web has been threaded through the machine and onto the winding shaft 14 preliminarily to the beginning of a winding operation, the riding roller is lowered into contact with the material on the winding shaft. This is accomplished by operating the switch 48 to cause the motor-driven shaft 52 to rotate clockwise, Fig. 3, which action permits the pivot shaft 42 to follow the shaft 52 under the pull of gravity effective on the pivot shaft system until arrested by the winding shaft and the material thereon.

As the roll of material builds up the riding roller 20 is free to follow upwardly as it bears on the surface of the roll because of the one-way clutch by which the pivot shaft 42 and the outer race 56 is allowed to rotate counterclockwise (Fig. 3) with respect to the inner race 55. The engaging elements or sprags 59 become ineffective for transmitting motion between the two races during the winding operation.

To raise the riding roller from the roll of material, the switch 48 is closed to run the motor 46 in the direction for rotating the shaft 52 counter-

clockwise, Fig. 3. The pivot shaft 42 is driven through the clutch 43 in this direction of rotation. The motor is automatically stopped when the riding roller reaches a predetermined position. This is accomplished by the opening of the motor switch 62. The motor switch is mounted on the frame of the machine at a place adjacent the collar 57 which rotates with the pivot shaft 42 (Figs. 1, 3 and 6). The opening of the switch is controlled by a cam 63 whose position is circumferentially settable around the collar 57 by a band 64. The band and cam can be clamped in any desired position by the bolt 65, Fig. 6. As the cam 63 is rotated counterclockwise, Figs. 3 and 6, it comes into contact with a follower 66. The follower is carried by a pivoted switch-engaging member 67 which is rocked by the cam to open the switch 62 when the riding roller 20 has been raised a desired amount.

It is important that the pressure which the riding roller 20 exerts on the roll of material be controllable. The pressure of the riding roller 20 is adjustable so as to enable the winding of material of different kinds and for producing rolls of the same material for different uses.

The pressure of the riding roller is a function of the resultant moment which is exerted on the pivot shaft 42. This moment is affected by the riding roller 20, the arms 36, 39 and 40, and by other devices which are secured to the pivot shaft and collectively referred to as the pivot shaft system. In the present winding machine this system includes a pair of arms 68 and 69 and a rod 70 extending therebetween. The arms 68 and 69 are spaced apart and are symmetrically located with respect to the bearings 71 and 72 of the pivot shaft 42 and the arms 39 and 40 of the riding roller 20 so as to effect distribution of the torsional strains in the pivot shaft.

The rod 70 may assume any suitable form. It is provided at its ends with screws 73, 74, which extend through slots 75 and 76 in the respective arms. The slots extend laterally with respect to the axis of the pivot shaft 42. The moment caused by the weight of the rod 70 may be varied by moving the rod along the slots and by clamping it to the arms in the location desired with the screws 73 and 74.

The arms 68 and 69 are adjustably fastened to the pivot shaft 42. Their inner ends encircle the pivot shaft and are split and provided with bolts 77 and 78 which are tightened to seize the split inner ends of the arms about the pivot shaft. The moment caused by the arms 68 and 69 and the rod 70 may be varied by angularly displacing the arms 68 and 69 about the pivot shaft 42, which has the effect of increasing or decreasing the resultant moment of the pivot shaft system by which the riding roller 20 is pressed against the surface of the roll of material, depending upon the located position of the arms. When a very tight center or a hard package is desired, the arms 68 and 69 and the rod 70 may be swung to a position across the axis of the shaft 42 and towards the winding rollers so as to add their moment to the moment of the riding roller 20 and its associated arms. When the desired resultant moment is obtained, the arms are clamped to the pivot shaft 42 by the bolts 77 and 78. In addition to the radial and angular adjustability of the distribution of weight thus obtainable, further refinement of adjustability may be obtained by selecting a rod 70 from a graduated series of similar rods of different weights. This construction is particularly advantageous for adapting a ma-

chine for winding many different kinds of materials.

What is claimed is:

1. In a winding machine having two surface winding rollers rotatable in the same direction and spaced apart to support therebetween a winding shaft within a roll of flexible material, and driving means for rotating one of said winding rollers to cause a roll of flexible material to be accumulated on said winding shaft, the combination comprising a pivot shaft, a riding roller engageable with the surface of the material on said winding shaft, a pair of arms carried by said pivot shaft and rotatably supporting said riding roller, said arms and said riding roller being biased towards the surface of the flexible material being wound on said shaft during a winding operation, means for controlling the lowering of said riding roller into contact with the surface of flexible material accumulated on said winding shaft and for elevating said riding roller from the surface of said flexible material, said last-named means including a reversible motor, a one-way clutch with a driving element having connection with said motor and a driven element connected to said pivot shaft, said driving element being capable of overrunning said driven element after said riding roller has been lowered into engagement with said roll of flexible material, and means for operating said reversible motor in one direction to elevate said riding roller and in the opposite direction to support and at the same time lower said riding roller into contact with said roll of flexible material.
2. In a winding machine having two surface winding rollers rotatable in the same direction and spaced apart to support therebetween a winding shaft within a roll of flexible material, and driving means for rotating one of said winding rollers to cause a roll of flexible material to be accumulated on said winding shaft, the combination comprising a reversible motor, a speed reducer driven by said motor, a pivot shaft, a riding roller carried by said pivot shaft, said pivot shaft and said riding roller being biased to rotate said pivot shaft to lower said riding roller, a one-way clutch between said speed reducer and said pivot shaft, and circuit means operable for causing the operation of said reversible motor to rotate said clutch and pivot shaft in one direction to elevate said riding roller and operable for causing the operation of said reversible motor to rotate said clutch and pivot shaft in the opposite direction to support and at the same time lower said riding roller into contact with the surface of said roll of flexible material.
3. In a winding machine having two surface winding rollers rotatable in the same direction and spaced apart to support therebetween a winding shaft within a roll of flexible material, and driving means for rotating one of said winding rollers to cause a roll of flexible material to be accumulated on said winding shaft, the combination comprising a pivot shaft, a riding roller engageable with the surface of the material on said winding shaft, a pair of arms carried by said pivot shaft for supporting said riding roller, means for lowering said riding roller to bring it into contact with the surface of flexible material accumulated on said winding shaft and for elevating said riding roller from the surface of said flexible material, said last-named means including a circuit and a reversible motor, a clutch with a driving element having connection with said motor and a driven element connected to said

pivot shaft, a switch in said circuit for operating said motor in one direction to elevate said riding roller and in the opposite direction to lower said riding roller, and a second switch in said circuit, said second switch being operated by the elevating movement of said riding roller when said riding roller has been elevated a predetermined distance from the surface of the flexible material accumulated on said winding shaft.

4. In a winding machine having two surface winding rollers rotatable in the same direction and spaced apart to support therebetween a winding shaft within a roll of flexible material, and driving means for rotating one of said winding rollers to cause a roll of flexible material to be accumulated on said winding shaft, the combination comprising a pivot shaft located to one side of said winding rollers, a riding roller engageable with the surface of the flexible material on said winding shaft, a pair of arms carried by said pivot shaft and having bearings for rotatably supporting said riding roller, means for transmitting motion from one of said winding rollers to said riding roller, means supported from said pivot shaft and constructed and arranged to apply a moment to said pivot shaft acting oppositely to the resultant moment on said pivot shaft by which said riding roller is biased towards and pressed upon the surface of the flexible material on said winding shaft, a reversible motor, a speed reducer drivable only from said motor, a one-way clutch having a driving element connected to said speed reducer and a driven element connected to said pivot shaft, and means for operating said reversible motor in one direction to elevate said riding roller and in the opposite direction to control the lowering of said riding roller into contact with the surface of said roll of flexible material.

5. In a winding machine having two surface winding rollers rotatable in the same direction and spaced apart to support therebetween a winding shaft within a roll of flexible material, and driving means for rotating one of said winding rollers to cause a roll of flexible material to be accumulated on said winding shaft, the combination comprising a pivot shaft located to one side of said winding rollers, a riding roller engageable with the surface of the flexible material on said

winding shaft, a pair of arms carried by said pivot shaft and having bearings for rotatably supporting said riding roller, means for transmitting motion from one of said winding rollers to said riding roller, a second pair of arms spaced apart on said pivot shaft, a rod extending between said last-named arms, means enabling the positioning of said arms in different angular positions about the axis of said pivot shaft to so locate said arms and rod to obtain a desired resultant moment on said pivot shaft and by which said riding roller is pressed upon the surface of the material on said winding shaft, and means for rotating said pivot shaft.

10 6. In a winding machine having two surface winding rollers rotatable in the same direction and spaced apart to support therebetween a winding shaft within a roll of flexible material, and driving means for rotating one of said winding rollers to cause a web of flexible material to be accumulated on said winding shaft, the combination comprising a pivot shaft located to one side of said winding rollers, a riding roller engageable with the surface of the flexible material on said winding shaft, a pair of arms carried by said pivot shaft and having bearings for rotatably supporting said riding roller, means for transmitting motion from one of said winding rollers to said riding roller, a second pair of arms spaced apart on said pivot shaft, a rod extending between said last-named arms, means adjustably supporting said rod on said arms for enabling a change in the distance of said rod from the axis of said pivot shaft, and means for rotating said pivot shaft.
